UNITED STATES PATENT OFFICE.

JOHN ERBEN, OF CLEVELAND, OHIO, ASSIGNOR TO THE H. FRANKE STEEL RANGE COMPANY, OF SAME PLACE.

STOVE OR RANGE.

SPECIFICATION forming part of Letters Patent No. 610,941, dated September 20, 1898.

Application filed July 30, 1897. Serial No. 646,541. (No model.)

To all whom it may concern:

Be it known that I, JOHN ERBEN, a citizen of the United States, residing at Cleveland, in the county of Cuyahoga and State of Ohio, have invented certain new and useful Improvements in Stoves or Ranges; and I do declare the following to be a full, clear, and exact description of the invention, such as will enable others skilled in the art to which it appertains to make and use the same.

My invention relates to stoves and ranges and seeks to improve that type of stove and range which comprises a casing, an oven disposed above the bottom wall of the casing so as to form a lower horizontal flue and having its side walls arranged at a distance from the side walls of the casing so as to form vertical flues in communication with the lower horizontal flue, an ash-box of less width than the oven arranged above the middle of the same, a fire-box arranged above and corresponding in width at its bottom to the ash-box and having outwardly-flared side walls serving in conjunction with the top of the casing to form horizontal flues, and an upright flue connected with the lower horizontal flue.

The invention will be fully understood from the following description and claim when taken in conjunction with the annexed drawings, in which—

Figure 1 is a vertical transverse section of a stove or range embodying my invention, and Fig. 2 is a vertical longitudinal section taken in the plane indicated by the line xx of Fig. 1.

Referring by letter to the said drawings, A indicates the casing of my improved stove or range, which is preferably constructed of steel plate and is of the ordinary rectangular form. This casing A has a plurality of holes a in its top wall b , which are normally closed by removable lids c , and it is also provided on said top wall b with a collar-flange d , which surrounds an opening d' and is designed for the ordinary connection of a smoke-pipe e , as shown in Fig. 1 of the drawings.

B indicates an upright flue which is arranged at the back of the stove or range in communication with the opening d' in the top and has the opening g below the top for a purpose presently described, and C indicates

an oven, both flue and oven being preferably constructed of steel plates. The said oven C extends from the flue B to the front of the casing, where it is provided with a door D, and it is disposed about the proportional distance illustrated from the end walls h of the casing A to afford flues E and is also disposed about the distance shown above the bottom wall f of the casing to form a flue F, which is in constant communication with the flues E, as shown, and is preferably provided with a cleaning-door G. The flues F and B are connected by an opening i , (see Fig. 2,) and in order to prevent a too direct passage of smoke and products of combustion from the flues E to the flue B the vertically-disposed baffle-strips H are provided in the flue F, as shown. These strips H extend from the rear wall L of the flue F to a point adjacent to the front wall of the casing A, and, being disposed on either side of the opening i , they serve to cause the smoke and other products of combustion to pass in close proximity to all parts of the bottom wall of the oven, so as to insure an even heating of said wall throughout its area. The said strips H are connected to the casing-wall f and the bottom wall of the oven by bolts j , and they are consequently enabled to serve the additional function of supports for the oven, as will be readily appreciated.

Above the oven C is disposed an ash-box I, which has a door J for the convenient introduction and removal of an ash-pan K. This ash-box I extends from the flue B or from the inner rear wall L of the stove to the front wall thereof; but it is considerably less in width than the oven C and is disposed above the middle of the same, as best shown in Fig. 2, so as to expose a considerable portion of the area of the top wall k of the oven to the direct contact of the products of combustion, as will be presently pointed out.

Above the ash-box I is disposed the fire-box M, which extends from the wall L to the front wall of the casing A and has a suitable grate N in its bottom, as shown. At its bottom this fire-box M corresponds in width to the ash-box I; but from such point its side walls P are flared so as to increase its capacity and afford a larger surface of fire, which is desirable in order to evenly heat the

- top wall *b* of the casing. The said walls *P* merge at their upper edges into horizontal walls *Q*, and these walls *Q*, which serve in conjunction with the top casing-wall *b* to form 5 a flue or flues *R*, merge, in turn, into depending walls or skirts *S*, which form the vertical flues *E'* in alinement with the flues *E*, and serve to prevent a direct passage of the flame and products of combustion to the top wall of 10 the oven *C*, and thereby obviate a too high heating of said wall, which would result in scorching the top of the substance being baked. This is an important feature of my invention, because it effectually prevents 15 scorching of the top of the article being baked before the other parts of the same are cooked, which is a desideratum. The depending walls or skirts *S* also tend to prevent the deposit of soot and other products of combustion on 20 the top wall *C*, and consequently the said wall will be sufficiently heated, notwithstanding the fact that there is no direct passage of the flame and products of combustion to the same.
- 25 *T* indicates a damper for controlling the opening *g*. This damper *T* is shown as fixed to and movable with a rock-shaft having a crank at one end; but it is obvious that it might be opened and closed in any suitable 30 manner and through the medium of any preferred device. Said damper *T* is designed to be opened when a fire is first started to permit of a direct passage of the smoke and other products of combustion to the smoke-pipe *e*; 35 but when the fire is well started it is closed, so as to compel the smoke, flames, and other products of combustion to take the course indicated by arrows. This course is from the fire-box through the flues *R*, the flues *E*; the 40 flue *F*, the opening *i*, and the flue *B* to the smoke-pipe *E*. In consequence of such passage of the flame and other products of combustion it will be observed that the top, side, and bottom walls of the oven will be subjected to a uniform degree of heat, which will 45 preclude the possibility of any part of an article in the oven being baked faster than the remainder thereof.

It will be observed that by reason of the

construction of the fire-box *M* and the arrangement of the same adjacent to the top wall of the casing the said top wall will be highly and uniformly heated throughout its area, so as to quickly cook any substance that may be placed in cooking utensils thereon. Again it 50 will be noticed that the arrangement of parts described permits of the oven being made very large without the necessity of the casing being any larger than the casing of an ordinary steel-plate range, which is an important 55 advantage and a desideratum in stoves and ranges.

Having thus described my invention, what I claim is—

The stove or range described comprising essentially a casing, the oven disposed above the bottom wall of the casing so as to form a low horizontal flue and having its side walls arranged at a distance from the side walls of the casing so as to form vertical flues *E* communicating with the lower horizontal flue, the upright flue *D* connected with the low horizontal flue, the ash-box of less width than the oven arranged above the middle of the same, the fire-box arranged above and corresponding in width at its bottom, the horizontal walls *Q* forming continuations of the side walls of the fire-box and serving in conjunction with the top of the casing to form upper horizontal flues *R*, and the skirts *S* depending from the outer edges of the walls *Q*; the said skirts serving in conjunction with the side walls of the casing to form vertical flues *E'* disposed in a plane above the oven and coincident with the flues *E*, whereby the 75 flame and products of combustion are conducted down to the lower horizontal flue and a direct passage of flame and products of combustion to the top wall of the oven and the deposit of soot and ashes thereon is prevented, as and for the purpose specified.

In testimony whereof I affix my signature in presence of two witnesses.

JOHN ERBEN.
